DESIGN FOR A GAS COOKSTOVE

Herbert M. Reeves, Kankakee, Ill., and Montgomery Ferar, Detroit, Mich., assignors to Florence Stove Company, Gardner, Mass., a corporation of Massachusetts

Application April 11, 1947, Serial No. 138,315

Term of patent 7 years

(Cl. D81—4)

To all whom it may concern:

Be it known that we, Herbert M. Reeves and Montgomery Ferar, citizens of the United States, residing at Kankakee, in the county of Kankakee ad State of Illinois, and Detroit, in the county of Wayne and State of Michigan, respectively, have invented a new, original, and ornamental Design for a Gas Cookstove, of which the following is a specification, reference being had to the accompanying drawing, forming a part thereof.

Figure 1 is a perspective view of a gas cookstove showing our new design, both sides of the stove being identical.

Fig. 2 is a fragmentary transverse sectional view taken approximately in the plane of line 2—2 of Fig. 1.

The dominant features of the design reside in the portions shown in full lines in the drawing.

We claim:

The ornamental design for a gas cookstove, substantially as shown and described.

HERBERT M. REEVES.
MONTGOMERY FERAR.
